HOOD CATCH

Filed Sept. 29, 1927

INVENTOR
RAY H. DAVIS.
BY
G. H. Harness
ATTORNEY

UNITED STATES PATENT OFFICE.

RAY H. DAVIS, OF FLINT, MICHIGAN, ASSIGNOR TO FYND PRODUCTS COMPANY, A CORPORATION OF MICHIGAN.

HOOD CATCH.

Application filed September 29, 1927. Serial No. 222,774.

This invention relates to catches and more particularly to hood catches adapted for use on automobiles.

One of the primary objects of my invention is to provide a simple and economical catch which will be void of rattles and which may be released simultaneously with the release of the hood and by the same movement as is required for the releasing of the hood.

With the above and other objects in view, my invention consists in the arrangement, combination and construction of the various parts of my improved device as described in the specification, claimed in my claims and shown in the accompanying drawings, in which:

The single figure is a vertical sectional view showing my improved device in operative position.

I have shown a member 5 which may correspond to the vehicle frame of a motor vehicle and which has secured thereto by rivets 6 an angle member 7 provided with a jaw 8 at the top thereof.

Over the member 5 is a sheet 9 which may correspond to a hood side piece and which has secured thereto by rivets 10 a somewhat U shaped bracket 11. The legs 12 and 13 of the bracket are provided with openings 14 and 15 thru which is extended a channel piece 16 having a jaw 17 adjacent the bottom thereof which is adapted to engage with the jaw 8 on the member 9. Vertical upward pull is exerted on the channel piece 16 and its jaw 17 by means of a coil spring 18 positioned within the channel piece bearing at its top on the top of the channel piece as at 19 and at its bottom against a struck out lug 20 on the bracket 11. The lug 20 extends under the bottom of the coil spring and tends to hold the same against lateral displacement as well as against vertical movement.

In order to hold the channel piece 16 and its jaw 17 resiliently pressed toward the jaw 8 when in assembled position I have provided an elongated spring member 21 having a turned up end 22 engaging the top of the leg 12 and a struck up portion 23 engaging the bottom of the leg 13 so as to definitely vertically locate the same. An inwardly bent leg 24 of the spring bears against the lower end of the channel 16 exerting a spring pressure thereon. This spring pressure is exerted both when the jaw 17 is engaged with the

jaw 8 and when the two are disengaged. It will be apparent that the channel 16 may swing in the openings 14 and 15 when the jaws are being engaged or disengaged. The opening 14 acts as the pivot point while the larger opening 15 provides for the greatest swinging movement.

A handle 25 is positioned on the outside of the hood side piece or plate 9 and is provided with a lever portion 26 which extends thru an opening 27 in the plate 9 and is pivotally secured as at 28 to the channel piece 16. A leg 29 on the lever 26 bears against the face of the jaw 8 when the two jaws of the catch are engaged so that the lever and its handle may be held against vibration, or rattling. When it is desired to disengage the jaws of the catch the handle 25 is raised upwardly, causing the lever 26 to pivot about its point 28 so that the leg 29 pushes against the jaw 8 moving the channel piece 16 inwardly against the pressure of the spring leg 24, thus the jaws are disengaged and the plate 9 simultaneously raised. When it is desired to engage the jaws downward pressure may be exerted on the handle 25 so as to simultaneously lower the plate 9 and push the channel piece 16 inwardly until the jaw 8 and jaw 17 are in position to be engaged.

It will be obvious that various changes may be made in the arrangement, combination and construction of the various parts of my improved device without departing from the spirit of my invention and it is my intention to cover by my claims such changes as may be reasonably included within the scope thereof.

What I claim is:

1. A catch of the class described comprising a fixed jaw member and a movable jaw member, an operating member for engaging and disengaging the jaw members, and independent resilient means constantly exerting pressure both laterally and vertically on the movable jaw member.

2. A catch of the class described comprising a fixed jaw member and a movable jaw member, an operating member for engaging and disengaging the jaw members, and resilient means exerting pressure both laterally and vertically on the movable jaw member, said means comprising springs pressing said jaw both laterally and vertically.

3. A catch of the class described compris-

ing a fixed jaw member, a movable closure member and a movable elongated member secured thereto, a jaw member on the elongated member adapted to engage the first 5 said jaw member, resilient means constantly tending to move the jaws together laterally, other resilient means constantly tending to move the jaws apart vertically, and operable means for overcoming said resilient 10 means to engage and disengage the jaws.

4. A catch of the class described comprising a fixed jaw member, a movable closure member and a movable elongated member secured thereto, a jaw member on the elongated member adapted to engage the first 15 said jaw member, resilient means tending to move the jaws together laterally and to move them apart vertically, said means comprising springs pressing the elongated member, 20 and operable means for overcoming said resilient means to engage and disengage the jaws.

5. A catch of the class described comprising a fixed jaw member, a movable closure 25 member and a movable elongated member secured thereto, a jaw member on the elongated member adapted to engage the first said jaw member, resilient means tending to move the jaws together laterally and to move 30 them apart vertically, said means comprising springs pressing the elongated member, and operable means for overcoming said resilient means to engage and disengage the jaws, said operable means comprising a 35 leverage device secured to the elongated member and pressed against the fixed jaw when the jaws are engaged.

6. A catch of the class described comprising a fixed jaw member, a closure member, a 40 pair of slotted bracket members secured on one side of the closure member, an elongated member extended thru the slots and adapted for a relatively wide swinging movement in one slot and slight swinging movement in 45 the other, a jaw on the elongated member adjacent the slot providing wide movement, operable means for moving the elongated means to engage and disengage the jaws, resilient means resisting swinging of the elongated member in the slots and constantly 50 directing lateral pressure against said elongated member, and resilient means constantly urging said jaw members apart in a vertical direction.

55 7. A catch of the class described comprising

ing a fixed jaw member, a closure member, a pair of slotted bracket members secured on one side of the closure member, an elongated member extended thru the slots and adapted for a relatively wide swinging movement in 60 one slot and slight swinging movement in the other, spring means constantly urging said elongated member upwardly, a jaw on the elongated member adjacent the slot providing wide movement, operable means for 65 moving the elongated means to engage and disengage the jaws, and resilient means independent of said spring means resisting swinging of the elongated member in the slots, said means comprising a spring secured 70 to at least one of said bracket members and bearing against a portion of the elongated member said spring constantly directing lateral pressure against the elongated member. 75

8. A catch of the class described comprising a fixed jaw member, a closure member, a pair of slotted bracket members secured on one side of the closure member, an elongated member extended thru the slots and adapted 80 for a relatively wide swinging movement in one slot and slight swinging movement in the other, a jaw on the elongated member adjacent the slot providing wide movement, operable means for moving the elongated 85 means to engage and disengage the jaws and resilient means resisting swinging of the elongated member in the slots, said means comprising a spring secured to at least one of said bracket members and bearing against 90 the elongated member adjacent the jaw thereon.

9. A catch of the class described comprising a fixed jaw member, a closure member, a pair of slotted bracket members secured on 95 one side of the closure member, an elongated member extended thru the slots and adapted for a relatively wide swinging movement in one slot and slight swinging movement in the other, a jaw on the elongated member 100 adjacent the slot providing wide movement, operable means for moving the elongated means to engage and disengage the jaws and resilient means resisting swinging of the elongated member, said means comprising 105 an elongated spring secured to said bracket members and having a portion extended to and pressing against the said elongated member.
